UNITED STATES PATENT OFFICE.

ALBERT ROSENBERG, OF BALTIMORE, MARYLAND.

ANNUNCIATOR.

SPECIFICATION forming part of Letters Patent No. 395,251, dated December 25, 1888.

Application filed May 23, 1888. Serial No. 274,809. (No model.)

To all whom it may concern:

Be it known that I, ALBERT ROSENBERG, a citizen of the United States, residing at Baltimore, in the State of Maryland, have invented 5 new and useful Improvements in Annunciators, of which the following is a specification.

This invention relates to mechanical annunciators, in contradistinction to electrical annunciators, for buildings, more especially 10 for private dwellings; and it has for its objects to provide novel means for operating the signal-plates; to provide novel devices for supporting the signal-plates away from the sight- 15 openings in the signal box or case; to provide novel means for releasing the signal-plates and permitting them to fall over the sight- openings, and to provide novel means for operating the audible signal. These objects I 20 accomplish by the features of construction and combinations of devices hereinafter described and claimed, reference being made to the accompanying drawings, illustrating my invention, in which—

Figure 1 is a front elevation of the signal- 25 box, showing the signal-bell and connections for leading to two apartments or to doors of apartments in a building; Fig. 2, an inside view of the signal-box, looking at the rear of the signal-plates; Fig. 3, a vertical broken 30 sectional view taken on the line $x-x$ of Fig. 2; Fig. 4, a detail perspective view of the locking-bar and pawl for holding a signal-plate away from the sight-opening in the signal- 35 box; Fig. 5, a detail perspective view of a signal-plate; Fig. 6, a detail sectional view taken on the line $y-y$, Fig. 2.

In order to enable those skilled in the art 40 to make and use my invention, I will now describe the same in detail, referring to the drawings, wherein—

The numeral 1 indicates the signal box or case, of rectangular or other form suitable for the conditions required, and having a vertical face-plate, 2, provided with the required number of sight-openings 3, above which and upon 45 or adjacent to the face-plate is located a horizontal bar, 4, having end bearings, 5, for the journals of a horizontal crank-shaft, 6, one end of which extends through the box and is 50 furnished with a suitable handle, as at 7, whereby the shaft may be turned or rocked. The signal-plates 8 are square and flat, and

each has an attached curved shank, 9, pivoted to the lower end of a bracket, 10, depending from and secured to the horizontal bar 4, and 55 to the latter are also attached pendent arms 11, to each of which is pivoted intermediate its ends, as at 12, a bar, 13, arranged to vertically oscillate on its pivot in a plane parallel to the face-plate. This bar at one end, 14, 60 is connected by a wire, cord, or similar connection, 15, with an apartment or door of a building remote or at a distance from the signal-box, while the opposite end carries a bevel-faced pawl, 16, pivoted at 17, and having a 65 tail-piece, 18, extending beyond the pivot and acted on by a suitable spring, 19, which normally holds the pawl in a horizontal position or in the same plane as the bar.

The bars 13 are so arranged that the bevel 70 faces of the pawls are directly above and in the path of the curved shanks of the signal-plates, so that when the latter are swung upward in the arc of a circle on their pivotal attachment, as hereinafter explained, the said 75 shanks will tip the pawls upward and ride past the bevel faces thereof until the shanks are brought to a position above the pawls, when the springs 19 will, by acting on the tail-pieces, restore the pawls to their normal position in line with the bars 13, so that the shanks rest upon the upper sides of the pawls, 80 and the signal-plates are thereby held away from the sight-openings 3 in the signal-box. The signal-plates are raised to the position 85 described by connecting each with the horizontal crank-shaft 6 through the medium of a cord or other flexible connection, 20, so that when the crank part of the shaft is elevated 90 by turning the handle 7 the signal-plate (one or more) which may be down over the sight-opening is lifted therefrom out of view. The bars 13 at their end portions 14 are each connected with one end of a spiral or other spring, 95 21, the opposite end of which is secured, as at 22, to the face-plate of the signal-box, and said end portion, 14, of each bar connects by a cord, wire, or other device, 23, with one arm of a bell-crank lever, 24, pivoted at its angle 100 to a support, 25, in the signal-box, and having its other arm connected by a cord or wire, 26, with an audible signal—such as a bell, 27—for indicating attention to the annunciator when a call is made. In the present instance

the audible signal is shown as simply a bell of the well-known clapper style mounted on a pivoted spring-arm, 28, to which the cord or wire 26 is attached.

5 In practice the cords or other connections 15 will extend to the apartments or to the doors of apartments through the medium of ordinary bell-crank levers, 29, Fig. 1, and will be provided with any suitable pulls or handles, which latter it is not deemed necessary to illustrate. When a call is to be made, the person in the apartment or at the door of an apartment manipulates the pull or handle, which thereby draws the connection 15, and 15 lifts the end portion, 14, of the bar 13 and depresses the opposite or pawl-carrying end until the pawl is so far lowered as to be withdrawn as a support to the shank of the signal-plate, whereupon the latter will fall by 20 gravity over a sight-opening. At the same time that the end 14 of the bar 13 is raised, as stated, to release the signal-plate, the cord or wire 23 is drawn, and the bell-crank lever 24 is rocked to pull the cord or wire 26 and 25 cause the bell 27 to sound the signal that a signal-plate has been operated. When the pull or handle is released by the person after effecting the call, as stated, the spring 21 retracts the raised end 14 of the bar 13 and 30 causes its pawl end to rise until the bar and pawl stand in a horizontal plane, or approximately. The attendant at the office or signal box then operates the crank-shaft 6, causing its cord 20 to raise the signal-plate until its 35 shank rides past the pawl and rests thereupon to hold it away from the sight-opening. It will be obvious that as the connections 20 between the crank-shaft and signal-plates are flexible one of the latter can be raised 40 without disturbing any other.

The signal-plates will in practice be provided with the desired character to indicate the point from which the call is made, and the number of signal-plates, pawl-carrying bars, 45 and necessary adjuncts will correspond with the number of apartments or doors from which calls are to be made.

The annunciator is more especially designed for private dwellings to call servants; but obviously it can be used in hotels and other places where such contrivances may be desired.

What I claim is—

1. The combination, with a vertically-movable signal-plate arranged within a suitable casing having a sight-opening, of a bar pivoted to swing in a vertical direction, and having at one end a pivoted pawl arranged in the path of the arm carrying the signal-plate, and a 55 wire or cord connected with the other end of the bar and leading to a point from which a call is to be made, substantially as described.

2. The combination, with a suspended swinging signal-plate having a pivoted shank arranged in a suitable casing, of a pawl-carrying bar pivoted between its ends, a pawl pivoted to one end of the bar and arranged in the path

of the pivoted shank, and a wire or cord connected with the opposite end of the bar and leading to the point from whence the call is made, substantially as described. 70

3. The combination, with a suspended swinging signal-plate having a pivoted shank, of the pawl-carrying bar pivoted intermediate its ends, a pawl pivoted to one end of the bar, 75 and a wire or cord connected with the opposite end of the bar and leading to the point from whence the call is to be made, substantially as described.

4. The combination, with a signal-box having a sight-opening and an audible signal, of a pivoted signal-plate arranged in said casing to swing in front of said opening, a pawl-carrying bar pivoted intermediate its ends, a pawl pivoted to one end of the bar and having its end arranged in the path of movement of the shank carrying said signal-plate, and wires or cords respectively connecting the opposite end of the bar with the signal and the point from which the call is to be 85 made, substantially as described.

5. The combination, with the signal-box having a sight-opening and a crank-shaft in the box, of the pivoted signal-plate, a flexible connection between the crank-shaft and signal-plate, the horizontal pawl-carrying bar pivoted between its ends, and having at one 95 end a pivoted spring-pawl arranged in the path of movement of the shank or arm carrying the signal-plate, and a wire or cord connecting the opposite end of the bar with the point from whence the call is to be made, substantially as described. 100

6. The combination, with a signal-box having a sight-opening, a crank-shaft in the box, 105 and a signal-bell, of a pivoted signal-plate, a flexible connection between the shaft and signal-plate, a horizontal bar having at one end a pivoted pawl arranged in the path of the shank or arm carrying said signal-plate, upwardly and downwardly extending cords or 110 wires connected with the opposite end of the bar, and a bell-crank lever having one arm connected with the downwardly-extending cord or wire and the other arm connected with the signal-bell, substantially as described. 115

7. The combination, with the signal-box, of the suspended signal-plate having a shank pivoted at its upper end, means for raising the signal-plate and its shank, a horizontal bar having at one end a pivoted pawl past 120 which the shank rides when elevated, a cord or wire connected with the opposite end of the bar for raising the same to depress the pawl and release the signal-plate, and a signal—such as a bell—connected with the end of the bar opposite the pawl, substantially as described.

8. The combination, with a signal-box, of the horizontal stationary bracket, the signal-plate having a shank pivoted to said bracket, 130 the horizontal bar having at one end a pawl pivoted to the bar and provided with a tail-piece, a spring acting on the tail-piece to nor-

5 mally hold the pawl in line with the bar, means for raising the signal-plate and moving its shank past and to a point above the pawl, a cord or wire connected with the end of the bar opposite the pawl and extending to the point from whence the call is to be made, and an audible signal connected with the said opposite end of the bar and operated when the latter is elevated, substantially 10 as described.

9. The combination, with a signal-box having a face-plate provided with a sight-opening, of a suspended swinging signal-plate, a 15 bar pivoted between its ends to oscillate in a vertical plane parallel to the face-plate, a pawl pivoted to one end of the bar, means for

swinging the signal-plate past the pawl, a cord or wire connected with the end of the bar opposite the pawl and leading to the point from whence the call is to be made to 20 oscillate said bar and depress the pawl, a retracting-spring for restoring the bar to its normal position, and an audible signal connected with the bar and operated when the pawl is depressed, substantially as described. 25

In testimony whereof I affix my signature in presence of two witnesses.

ALBERT ROSENBERG.
